UNITED STATES PATENT OFFICE.

PATRICK J. CLIFFORD, OF FALLS, PENNSYLVANIA, ASSIGNEE TO TRAIN CONTROL CORPORATION OF AMERICA, OF SCRANTON, PENNSYLVANIA, A CORPORATION OF DELAWARE.

SYSTEM OF ELIMINATING AUTOMATIC TRAIN-CONTROL APPARATUS.

Substitute for abandoned application Serial No. 667,722, filed October 10, 1923. This application filed January 27, 1923. Serial No. 250,035.

In an application for Letters Patent of the United States filed by me March 24th, 1919, Serial Number 284,731, I describe a train stop system in which an eliminating valve is employed to prevent the operation of the automatic mechanism and an automatic application of the brakes when the engineer reduces speed by making a manual service application of the brakes, by operating his automatic 5 brake valve.

In air brake systems as generally constructed there is a valve known as the dead head valve which is located in the train pipe under the engineer's automatic brake valve. 15 This valve is closed when an engine is coupled onto a train as a second engine, the purpose of closing the valve being that this engine, so far as the application of the brakes is concerned, is rendered dead and the operation of applying the brakes is entirely within 20 the control of the engineman of the first engine.

It is one object of my present invention to provide means whereby when an engine, having 25 an automatic braking apparatus including an eliminating means mounted thereon, is coupled to the train as the first or sole engine, and by mistake or otherwise, has its dead head valve closed, the eliminating 30 means which is intended to prevent automatic braking will be nullified, so that the engineer can not under these circumstances eliminate automatic braking, but on the contrary, automatic braking will go on when the 35 caution or danger board is reached and the train will be brought to a stop, notifying the engineer that the dead head valve has been wrongly set in closed position, and thus impelling him to correct the fault.

With prior automatic systems it would be 40 possible for the engineer, if he were disposed to disobey the rules, to eliminate automatic braking without making a manual service application of the brakes. To do this he 45 would close his dead head valve, which would prevent him from making a train pipe reduction when he set his automatic service valve H^6 in service position. The placing of his valve in service position would eliminate automatic braking, so that we would then have 50 a condition which would enable the engineer

to defeat automatic braking without reducing the speed of his train. This contingency is one that would arise only from an exceptional condition, because this dead head valve 55 is one that is intended to be manipulated only when an engine is coupled up as a second engine. However, to extend the element of safety to its full limit, it is desirable to remove the possibility of this exceptional condition or circumstance existing. This application is filed as a substitute for my now abandoned application, Serial No. 667,722, filed October 10, 1923.

The invention is shown in the accompanying drawings, in which:

Figure 1 is a diagram of my automatic system in connection with one known form of braking apparatus, for instance, the Westinghouse system, parts of which are shown 70 in dotted lines.

Fig. 2 is a view of the trigger valve.

Fig. 3 is a view of the contact valve.

Fig. 4 is a view of the engineer's brake valve H^6 . 75

Fig. 5 is a view of the eliminating valve.

Fig. 6 is a view of the automatic air release valve.

Fig. 7 is a view of my improved dead head valve and associated parts. 80

Fig. 8 is a view of another form of the invention.

In these drawings I have shown the automatic braking system as operable from a ramp, through a contact roll 1, but it will 85 be understood that the invention is not limited in this regard, as the automatic system may be operated from the electrical condition of the traffic rail system of the railway.

In this system the operation of the contact 90 roll 1 moves a valve shown generally at 3, which supplies equalizing reservoir air pressure through a pipe 8 and pipe 14 to a cylinder a of a trigger valve 19. This valve is thereby opened to supply equalizing reservoir air through branch pipe 13 and pipe 15 to an automatic air release valve shown generally at A so that when this valve is opened train line air will be discharged to atmosphere through a port 44' for the automatic 100 application of the brakes and the stoppage of the train. As a part of this automatic sys-

- tem there is also an engineer's disabling valve B to which equalizing air pressure is supplied through the trigger valve 19 so that the engineer will be prevented from interfering 5 with the automatic application of the brakes when the automatic action is to take place. This disabling valve receives its air pressure from pipe 15 by way of a part of the valve organization A through a pipe 51, and when 10 pressure exists in this last named pipe the valve B will be closed and prevent the access of air from the main reservoir X to the engineer's big brake valve H^e, known in the Westinghouse system as the engineer's automatic 15 brake valve. The engineer will therefore be prevented from obtaining a supply of air from the main reservoir for recharging the train line and interfering with the automatic braking.
- 20 This disabling valve is located in the piping 50^a, 50, extending from the main reservoir and connected up with the engineer's brake valve H^e for supplying it with main reservoir pressure.

25

Eliminating valve.

- For eliminating the automatic braking mechanism when the engineer makes a service application of the brakes, an eliminating 30 valve B' is provided in the pipe 15 leading to the automatic air release valve A. This valve is normally open so that air pressure is free to pass through the pipe 15 to the automatic air release valve A when the trigger valve 19 is open. When, however, the engineer makes 35 a manual service brake application by placing his automatic valve H^e in service position, a supplemental air supply valve h^a is opened and air pressure goes through pipe 52 from the chamber above the rotary valve of 40 the engineer's automatic brake H^e to the upper side of the eliminating valve B', thus closing the same to shut the pipe 15 and prevent air from going from the trigger valve 19 to the automatic service valve organization 45 A, thus eliminating automatic braking during manual braking.

The "dead head" valve is shown at DH. The purpose of this valve when closed is to 50 cut out the engineer's automatic brake valve H^e, so that if the engine is to be used as a second engine in a train, its train braking mechanism will be cut out of operation and braking actions will then be under the sole control of the engineer of the first engine.

Suppose, however, by accident or otherwise the dead head valve on the first engine is closed, and that this valve is of the usual construction, this would prevent the engineer 60 from making a service application of the brakes by setting his valve H^e in service position, but it would not prevent the elimination of automatic braking.

In other words, supposing the valve DH to 65 be of the usual known construction and acci-

dently closed on the first engine, then when the engineer sets his automatic brake valve H^e in service position he would eliminate automatic braking by closing valve B', but he would not get a service application of the 70 brakes because the wrongly closed dead head valve DH would prevent him from reducing train line air pressure. He would therefore go by a caution or danger board at full speed and an accident might result.

To prevent this I have provided means whereby the possibility of eliminating automatic braking will depend upon the normal or open position of the dead head valve, and therefore if this is closed for any reason, then the engineer cannot eliminate automatic braking by operating his valve H^e, and he would get an automatic stop, which of course would notify him that his dead head valve is wrongly set, i. e. closed. Or if for any reason 80 the engineer attempted to defeat automatic braking without making a manual brake application (which could be done by closing the ordinary dead head valve) he would be prevented from doing so by the present improvement.

This improvement consists in employing the dead head valve as a cut off in the pipe 52 which supplies air pressure from the engineer's brake valve H^e to the eliminating valve. For this purpose the casing dh of the dead head valve is interposed in the pipe 52 and is provided with a passage 52^a connecting the sections of this pipe 52. This passage is controlled by the rotary plug member of the dead head valve DH, for which purpose said plug member is provided with a supplemental port dp which closes this passage when the dead head valve closes the train pipe. Therefore under this closed condition of the valve DH, even though the engineer sets his valve H^e in service position, there will not be any train pipe reduction, nor will there be an elimination of automatic braking take place, but on the contrary, the 95 brakes will be automatically applied. If, however, the dead head valve is open, then the engineer can manually apply the brakes and his act in doing this will cause elimination of the automatic action. He cannot 100 eliminate without applying the brakes.

Now it is of course necessary to eliminate the automatic apparatus on the second engine. This is done by coupling up the trigger valve organizations 19 of the two engines. For this purpose a pipe 15^x forming an extension of the pipe 15 is provided with the usual valved coupling 15^a to connect with the usual coupling member 15^y and the latter connects with the piston chamber 35 of the trigger valve on the second engine, so that when this trigger valve is open the air pressure will pass through pipes 15, 15^x to the chamber 35 of the trigger valve of the second engine and the action of this will be 110 115 120 125 130

nullified, despite the fact that the contact roll 1 of the second engine will strike the ramp and cause the valve to open.

The operation of the two trigger valves 5 may be stated as follows:

When the valve 19 of first locomotive is opened, air will go through 15 and 15^x and 15^y to chamber 35 of the second valve, and will immediately set the piston in this chamber over and retract the dog 26. It will also let air go into chamber *a'* of this valve, thus holding valve 19 of the second locomotive in closed position, so that when the second contact valve strikes the ramp the air let into

15 chamber *a* of the second valve will have no effect in throwing valve 19 (second) to locked position, because this is resisted by the pressure in chamber *a'* and because the dog 26 of the second valve will be retracted. 20 It may be noted, too, that there is a difference between the actions and course of air in holding the trigger valve of the second locomotive inactive or preventing it from being held open, and the action and course of air 25 in resetting the first valve, for the following reasons. In restoring the first valve to closed position, the air must build up in chambers 35 and *a'* through the minute port 15^a. This takes time. In respect to the second valve, however, the air for operating the piston in chamber 35 does not go through the small port 15^a of the second valve, but it enters the chamber directly through the supplemental pipes 15^x and 15^y which are as

30 large as the pipe 15. This will quickly operate piston 36 and retract the bolt 26. Furthermore, air in sufficient quantity will pass from chamber 35 through pipe 37 to chamber *a'* of the second engine, thus operating upon piston *b'* to hold the valve 19 in closed position. The small port 15^a does not enter 35 into this action at all.

Indeed, actual tests prove that the second trigger valve will not go over at all because 40 pressure will get into chamber *a'* and it requires but slight pressure here to counteract the pressure in chamber *a*. It requires but slight pressure in chamber *a'* of the second valve, or, in fact, either valve, to hold the 45 valve in closed position, because the pressure in chamber *a* is that which results from only a momentary opening of the contact valve 3, while the pressure behind the piston *b'* of chamber *a'* of the second trigger valve is full 50 and continued equalizing reservoir pressure say of 70 pounds, so long as the first valve is open.

The trigger valve must remain open to prolong the interval of time that the air is supplied to the automatic mechanism, because 60 the air inlet port 22' thereof is small as compared with the diameter of the pipe 15 and the capacity of the chamber in the valve A and the length of pipe 51.

65 The valve will remain open until pres-

sure builds up beyond it in pipe 15, the chamber of valve A and pipe 15 sufficiently, so that, passing back through the small port 15^a, it will operate the piston 36 and release the lock or trigger 26 of this valve, so that 70 the pressure passing through pipe 37 into chamber *a'* can restore the valve to closed position. A similar action takes place when the eliminating valve B' is closed, but the time interval is not so long. In the latter 75 case, say that it takes four seconds for this trigger valve to perform its cycle. The engineer, knowing this, will hold his valve H^o in service position at least this length of time, for he knows that if he did not do so, 80 the eliminating valve B' would open as soon as he returned valve H^o to release or running position, and he would know that he would get an automatic brake application because the trigger valve would still be open. 85 In holding his valve H^o in service position long enough to eliminate the automatic brake mechanism, he would get a service application of the brakes long enough to materially retard the train. He cannot therefore under any circumstances eliminate without slowing down the speed of the train. If he places his valve H^o back in release or running position immediately after placing it in service position, he would take air 90 away from the eliminating valve and this would open, this being due to the fact that the supplemental valve *h*² would close, cutting off the air supply, and air would escape from pipe 52 around the ball *h*⁴. 95

100 What has been said regarding the dead head valve DH applies to all cut out valves of the system on the engine. They all may be connected up in the pipe leading to the eliminating valve so that elimination of automatic braking can be accomplished only when all of these valves are open.

105 In Fig. 8 I show a connection for supplying brake pipe pressure to the under side of the eliminating valve when the cut out cock is closed to cut out the engineer's valve, so that if pressure is introduced to the upper side of the eliminating valve to close the same, this will be resisted by the pressure below the valve and it will remain open. 110 The cut out cock therefore has ports which will connect the train line with the under side of the eliminating valve when said cut out valve is set to make the engine dead, as to manual braking. 115

120 The engineer's disabling valve may be placed in a position other than that shown, that is, it may be placed in the train pipe so that the engineer cannot recharge the train pipe and release the brakes when this valve is closed.

125 This disabling valve may be opened, when, after a prescribed lapse of time, the air is bled away therefrom through port 56 of the automatic air release valve A, consequent 130

upon the restoration of this valve to closed position, when air is bled away therefrom through port 22" of the trigger valve when the latter is returned to closed position.

5 For opening this disabling valve air pressure may be derived from any suitable source, under the control of the engineer, as for instance, through pipe 57 from the engineer's independent brake valve S^6 , which gets its 10 supply, for restoring the disabling valve, from the application chamber of the distributing valve through the disabling valve release pipe x' , the air finally exhausting through port W of the disabling valve, which 15 then in effect becomes the exhaust port for the S^6 valve instead of the usual exhaust port at said valve.

I claim:

1. In combination in automatic train stop 20 systems, automatic train stop apparatus on the vehicle or engine, means for eliminating the function of said automatic apparatus as a consequence of the engineer setting his brake valve in service position and thus retarding the train, a cut out valve to render the engine dead so far as braking is concerned, so that said engine may be coupled up with a first engine to assist the same with its motive power, said eliminating means being nullified 30 when said cut out valve is closed, so that in case said valve is closed on the first engine, the automatic train stop means thereon will be effective, even though the engineer sets his automatic brake valve in braking position, substantially as described.

2. In combination in automatic train stop 40 systems, automatic train stop apparatus on the vehicle or engine, means for eliminating the function of said automatic apparatus as a consequence of the engineer setting his brake valve in service position and thus retarding the train, a cut out valve to render the engine dead so far as braking is concerned, so that said engine may be coupled up 45 with a first engine to assist the same with its motive power, said eliminating means being nullified when said cut out valve is closed, so that in case said valve is closed on the first engine, the automatic train stop means thereon will be effective, even though the engineer sets his automatic brake valve in braking position, said cut out valve when closed also closing the air passage leading from the engineer's automatic brake valve to the eliminating means to nullify the latter.

3. In combination in automatic train stop 55 systems, automatic train stop apparatus on

the vehicle or engine, means for eliminating the function of said automatic apparatus as a consequence of the engineer setting his 60 brake valve in service position and thus retarding the train, a cut out valve to render the engine dead so far as braking is concerned, so that said engine may be coupled up with a first engine to assist the same with its 65 motive power, said eliminating means being nullified when said cut out valve is closed, so that in case said valve is closed on the first engine, the automatic train stop means thereon will be effective, even though the engineer 70 sets his automatic brake valve in braking position, a valve on the engine to supply air to the automatic apparatus, means for automatically operating said valve, means for supplying air from the valve of the first engine 75 when open to the supply valve mechanism of the second engine when this is coupled up with the first engine for nullifying the second supply valve and thus preventing it from supplying air to the automatic system of the second engine for operating it, substantially as described.

4. In combination in automatic train stop 80 systems, automatic train stop apparatus on the vehicle or engine, means for eliminating the function of said automatic apparatus as a consequence of the engineer setting his 85 brake valve in service position and thus retarding the train, a cut out valve to render the engine dead so far as braking is concerned, so that said engine may be coupled up with a first engine to assist the same with its motive power, said eliminating means being nullified when said cut out valve is closed, so that in case said valve is closed on the first 90 engine, the automatic train stop means thereon will be effective, even though the engineer sets his automatic brake valve in braking position, a trigger valve on the engine to apply air to the automatic apparatus, means for automatically opening said valve, means for locking said valve in open position, means 95 acted on by pressure built up between said trigger valve and the automatic apparatus for resetting said valve to closed position, said valve having a bleed port for the discharge of air from the automatic apparatus when said trigger valve is closed, means for supplying air from the trigger valve of the first engine, when open, to the resetting means of the trigger valve of the second engine for holding this closed, substantially as described.

In testimony whereof, I affix my signature.
PATRICK J. CLIFFORD.
